ELECTRON TRIGGER TUBE

John B. Sponsler, Huntington, N. Y., assignor to
 International Business Machines Corporation,
 New York, N. Y., a corporation of New York

Application December 31, 1951, Serial No. 264,312

2 Claims. (Cl. 315—35)

1

This invention relates to vacuum tubes having more than one complete set of elements within a single envelope. In particular this invention relates to a dual triode type of vacuum tube wherein certain additional elements have been placed whereby the single envelope becomes a self contained trigger device equivalent to the well known Eccles-Jordan trigger conventionally used for switching circuits, storage circuits, electronic counters and the like.

The chief object of this invention therefore is to provide a simple circuit component contained within a single sealed envelope, the circuit component including all the necessary electrical and electronic elements comprising a trigger circuit.

Another object of this invention is to provide a self contained trigger circuit within a conventionally sized vacuum tube envelope whereby interchangeability of trigger components is easily accomplished in a multiple trigger component circuit.

Still another object of this invention is to provide an inexpensive electronic trigger utilizing some of the normal component elements of a vacuum in dual utility.

Other objects of the invention are apparent from the specification which follows and from the accompanying drawings, which comprise:

Fig. 1, showing an elevation view of the trigger tube with the shell cut away to reveal some of the internal connections;

Fig. 2, showing a sectional view along the line 2—2 of Fig. 1;

Fig. 3, which is a top view of the tube of Fig. 1;

Fig. 4, showing a sectional view of the tube of Fig. 1 along the line 4—4; and

Fig. 5, which is a circuit equivalent of the trigger tube.

With reference to Fig. 1, a conventional octal type base 10 is provided with a glass envelope or shell 11 containing the mica supporting washers 12 and 13 between which the tube elements are supported. In the view of Fig. 1 a center support rod 14 is provided to space the washers 12 and 13. On each side of the rod 14, spaced radially from it, are the anode supports 15 and 16 (see also Figs. 2, 3, and 4). Clamped about each anode support is an anode member, the anode member P1 being fixed to support 15 and the anode member P2 being fixed to support 16. Anode member P1 is also supported in the washer 12 by a tab T1 and in the washer 13 by tabs T3, the anode member P2 being similarly supported by a tab T2 in washer 12 and by tabs T4 in

2

washer 13. Within the enclosure formed by P1 are located grid supports 17 and 18 upon which the grid G1 (not shown) is supported. Similar grid supports 19 and 20 are located within the enclosure of P2 for supporting the grid G2 (not shown). Within each anode member enclosure are a cathode sleeve 21 surrounding a heater 22 (see Fig. 2). The cathode sleeves and heaters are of conventional design and need be described in no more detail.

In the description above there has been described a type of twin triode electron discharge device. The present invention, however, contemplates other elements not found in the conventional construction of such devices.

Referring again to Figs. 1 and 2, partially surrounding each anode member is a shield member, shield member 23 surrounding anode member P1 and shield member 24 surrounding anode member P2. Each shield member bears a predetermined capacitative relationship with the anode member with which it is associated, thereby forming a capacitor of which one plate is the shield member and the other plate is the anode member, there being a vacuum or gaseous dielectric space therebetween.

Referring now to Figs. 1, 2, and 4, the shield members are each supported by a rod projecting through the washer 12 and the washer 13, the shield 23 being supported by the rod 25 and the shield 24 by the rod 26. The rod 25 is bent over (see Fig. 1) and welded to the grid support 19 and the rod 26 is bent over and welded to the grid support 17. On the bottom of the washer 12 (see Fig. 4) an arc of conductive material R1 is deposited to contact both the tab T1 and the projection of the rod 25. A similar arc of conductive material R2 is deposited on the bottom of washer 12 to contact both the tab T2 and the projection of the rod 26. As a result of the above arrangements the anode member P1 is coupled capacatively and through the resistance path of the deposited material R1 to the grid G2 (see Fig. 5) of the triode of which P2 is the anode member, and the anode member P2 is coupled capacatively and through the resistance path of the deposited material R2 to the grid G1 (see Fig. 5) of the triode of which P1 is the anode member. Consequently the arrangement of the additional elements of the novel tube herein described in effect provide a self contained trigger circuit within the envelope or shell 11. A comparison of the above described arrangement with the equivalent circuit shown in Fig. 5, which is a standard Eccles-Jordan trigger cir-

cuit, bears this out. In Fig. 5 the trigger composed of the triodes V1 and V2 provides capacitative coupling between the grid 5 of V2 (or G2) and the anode 3 of V1 (or P1), there being also a resistance coupling by the way of R1. Similarly capacitative coupling is provided between the grid 4 of V1 (or G1) and the anode 6 of V2 (or P2), there being also a resistance coupling by the way of R2.

The unique tube described above has many advantages both technically and economically including the absence of soldered connections (all welded construction), self contained trigger components being sealed within an envelope providing shorter connections and freedom from corrosion, the anode member of each triode is utilized both as an anode and as one plate of a capacitor, the trigger unit is adapted to be changed in a manner similar to replacing a vacuum tube in a tube socket, and increased operational stability is obtained due to the compactness of the trigger circuit so provided.

While the specification by way of illustration has described a preferred embodiment as reflected in the drawings, the scope of the invention is in no way intended to be limited thereby except as set forth in the accompanying claims, which follow.

I claim:

1. An electronic tube comprising within a single envelope a pair of electron discharge devices, each said device having at least a control grid element and an anode element, a capacitor be-

tween the anode element of each of the pair and the grid element of the other of the pair, non-conductive supports commonly supporting all the said elements within the said tube, and a resistor between the anode element of each one of the pair and the grid element of the other of the pair, said resistors being deposited upon the said non-conductive supports.

2. An electronic tube comprising within a single envelope a pair of electron discharge devices, each said device having at least a control grid element and an anode element, a non-conductive support common to all the said elements within the said tube, a resistor between the anode element of each of the pair and the grid element of the other of the pair, said resistor being deposited upon the said support, and a capacitor between the anode element of each of the pair and the grid element of the other of the pair, the said capacitor partially including one of the said anode elements.
